UNITED STATES PATENT OFFICE.

SIMON GAINER, OF CHICAGO, ILLINOIS.

BOX-SPRING.

1,296,068.

Specification of Letters Patent.

Patented Mar. 4, 1919.

Application filed May 2, 1918. Serial No. 232,164.

To all whom it may concern:

Be it known that I, SIMON GAINER, a citizen of the United States, and a resident of Chicago, Cook county, and State of Illinois, have invented certain new and useful Improvements in Box-Springs, of which the following is declared to be a full, clear, and exact description.

This invention relates to furniture springs of that type known as box springs and has for its primary object to provide a sectional box spring of improved construction which may be readily and quickly assembled and taken apart. Another object is to provide a sectional box spring with attaching means between the sections, adapted to so connect the sections, one with the other, that the whole spring will act as a unitary device. Another object is to provide a detachably connected box spring of simple, substantial and practical construction, without materially increasing the cost of the same. With these and other objects and advantages in view, this invention consists in the several novel features hereinafter fully set forth and claimed.

The invention is clearly illustrated in the drawings accompanying this specification, in which:

Figure 1, is a plan, partly broken away, of a sectional box spring embodying a simple form of the present invention; Fig. 2, is a side elevation thereof; Fig. 3, is a detail side elevation of a fragment of a band of the spring structure, and showing one member of one of the attaching devices; Fig. 4, is a detail vertical section taken on the line 4—4 of Fig. 1; Fig. 5, is a plan of the hook member of one of the attaching devices; Fig. 6, is a side view thereof; Fig. 7, is a plan of the socket member of the complementary attaching device; Fig. 8, is a side view thereof, and Fig. 9, is a detail plan of a fragment of one of the springs and band showing a tie between them.

Referring to said drawings, the reference characters 10, 11, 12, designate a plurality of box spring sections, each of which is a substantial duplicate of the other. Three sections are shown and comprise a complete box spring embodying the present invention. Each section comprises a frame 13, of rectangular form, made of wood or metal as desired, and secured to said frame and extending up therefrom are coiled compres-

sion springs 14, of the common and well known type employed in box springs, said springs being bound together as usual. Surrounding said springs is a rectangular band 15, which is fastened to the outer rows of springs by wire, cord, clips or the like 16, (see Fig. 9) and said band lies in the same plane as the tops of the springs and moves down with the outer rows of springs when they are depressed. Said band is shown in the form of stout wire, but I do not wish to limit myself to such, as the band may be made of other material. It is understood that when the several sections of the box spring are placed side by side, all of the bands 15, lie substantially in one and the same horizontal plane.

Secured to the adjacent parallel portions 15^a, of the bands 15, are complementary attaching members 17, 18, that co-act to detachably connect the adjacent sections together. Several of said attaching members are arranged along the meeting edges of the sections to securely fasten the sections together at several places. Although but two attaching members are shown along the meeting edges of the sections, it is to be understood that as many may be used as is necessary to obtain strength and security.

The means, illustrated, for securing the attaching members 17, 18, to the bands 15, comprises a body or base portion 19, which bears indirectly against the band and two horizontal studs or lugs 20, that extend through vertical loops or eyes 21, formed on the band. Cotter pins 22, are inserted through holes in the studs behind the loops or eyes 21, to prevent disconnection between the attaching members and band. When a wire band is used, it may be bent to form the loops or eyes at the proper places along its length. It is to be noticed that the distance between the parts 15^a, of the band carrying the attaching members is slightly less than the distance between the side edges of the frame 13, below them. This is to provide space between the bands for the attaching members, at the same time permitting the mattress portion and frame members to come into close contact.

The attaching members 17, are formed with socket portions 23, the sockets 24, of which run parallel with edge of the section to which they are attached. Preferably said sockets are non-circular in cross section and

are shown as of rectangular shape. At the lower edge of the socket and immediately in front of its opening is a ledge 23^a, flush with the bottom wall of the socket, which ledge 5 acts as a guide when the sections are being attached.

The attaching members 18, have hook members 25, projecting from their outer faces, which hook members are constructed 10 and arranged to enter the sockets in connecting the sections together. The parts of the hook members which enter the sockets are shaped, in cross section, to fit therein, to thereby prevent any rotatorial or turning 15 movement of one attaching member upon the other, so that when one section is depressed at any place near its edge, adjacent another section, said other section will be moved down therewith. Preferably the extreme 20 ends of the hook members are rounded off to facilitate the entrance of the hook members into the sockets. Relative lengthwise movement of one section with respect to another is prevented by any simple means, as for instance, hooks 26, upon one section and eyes 27, upon the other section into which the hooks engage.

Preferably a tufted mattress section 28, is placed upon each spring section and secured 30 to the bands 15. Said mattress sections project beyond the bands 15, far enough to meet each other when the sections are attached together, thus forming, to all intents and purposes, a continuous mattress, extending over 35 the entire box spring. Ticking 29, covers the stuffing of the mattress and extends down to the frame 13, where it is secured to the underside thereof to thereby wholly inclose the springs. At the places where the attaching 40 members are secured to the band, holes are made in the ticking 29, for the passage of the studs or lugs 20. The bottom of each mattress may comprise a separate piece of material 30, secured to the ticking 29, and 45 fastened to the band, as by sewing it thereto by stitches 31, thereby firmly securing each mattress section to its spring section and preventing relative sidewise movement or shifting upon the springs.

50 It is to be observed that a number of the socket members 17, may be placed along one edge of each section, and a corresponding number of the complementary hook members 18, placed along the opposite edge of each 55 section in position to co-act with the socket members of any other section. When so constructed, the sections are interchangeable and any one may be placed at either side of the others. Thus, if the middle section begins to 60 sag after long usage, the foot or head section—that is, either of the end sections—may be exchanged for the middle section.

Obviously, the exact form of the complementary attaching members shown is not material to this invention, broadly considered,

as various forms of hook and socket members may be substituted for the ones illustrated, the essential feature being that they are permanently or fixedly secured to the band and that they co-act to bind the two adjacent 70 portions of the bands together in such manner that they will act as a unitary structure—the one moving with the other.

To attach the sections together, they are placed side by side and moved relative to 75 each other to insert the hooks into the sockets. The hooks 26, are then hooked into the eyes 27. To detach the sections from each other, the hooks 26, are unhooked from the eyes 27, and the sections moved relative to 80 each other to detach the hooks 25, from the sockets 24.

From the above it is obvious that the sections may be attached and detached from each other with little or no effort and that 85 inasmuch as the attaching members are permanently secured to the sections, they are not likely to be mislaid or separated from the sections.

It is to be understood that while I have 90 shown and described the invention as applied to bed springs, it may be used in other furniture where a spring structure is employed.

More or less variation of the exact details 95 of construction is possible without departing from the spirit of this invention; I desire, therefore, not to limit myself to the exact form of the construction shown and described, but intend, in the following 100 claims, to point out all of the invention disclosed herein.

I claim as new and desire to secure by Letters Patent:—

1. A box spring comprising a plurality 105 of spring sections, and detachably connected means at the meeting edges of said spring sections adjacent the tops thereof, for detachably connecting the spring sections together, said means being connectible 110 and disconnectible when the adjacent spring sections are moved lengthwise of each other.

2. A box spring comprising a plurality of substantially similar box spring sections, each having a rectangular band surrounding 115 the top of the spring portion and secured thereto, socket members fixedly secured on the corresponding sides of the bands of each section, and co-acting hook members fixedly secured on the opposite sides of the bands, the hooks of one section being adapted to engage the sockets of an adjacently placed section, to thereby detachably connect the bands.

3. A sectional box spring comprising a 125 plurality of substantially similar box spring sections each comprising a frame, a spring structure supported thereon, and having a binder extending around its upper edge, and means for securing together the adjacent 130

edges of said sections comprising socket members fixedly secured to corresponding edges of the binders and co-acting hook members fixedly secured to the opposite 5 edges of the binders, the hook members of one section co-acting with the socket members of each adjacent section to detachably connect the sections.

4. A sectional box spring comprising a 10 plurality of substantially similar box spring sections, each comprising a frame, a plurality of connected coiled springs secured thereto, a band surrounding the tops of the springs and secured thereto, and complementary 15 detachable attaching members fixedly secured to adjacent portions of the bands for detachably connecting the bands, said detaching members being connectible and disconnectible when the adjacent spring sections are moved lengthwise of each other.

5. A sectional box spring comprising a 20 plurality of box spring sections, each comprising connected coiled springs, a rectangular band surrounding and secured to said 25 springs, said band being formed with eyes along two of its parallel sides, complementary detachable attaching members for said sections, each having studs extending through

said eyes of the band and means for securing said studs in said eyes. 30

6. A sectional box spring comprising a plurality of substantially similar box spring sections, each having a coiled spring structure surrounded by a rectangular band which is secured to the spring structure, a mattress section secured upon each box spring section and a covering extending along the sides of each section, complementary, detachable attaching members fixedly secured to the adjacent sides of said bands, 35 and means for preventing movement of any section in a direction parallel with the meeting edge of an adjacent section. 40

7. In a sectional box spring, a plurality of box spring sections, each having a spring structure and a rectangular band, secured thereto at the top, attaching members for detachably securing said sections together, comprising socket members fixedly secured to the band of one section and each formed with a ledge in front of the opening to the socket, and hook members fixedly secured to the band of an adjacent section, and each having a hook adapted to enter the companion socket on the adjacent section. 45

SIMON GAINER.
